DESCRIPTION

FIG. 1 is a first perspective view of a protective seal showing my new design;

FIG. 2 is a second perspective view thereof;

FIG. 3 is a front elevation view of thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.
